UNITED STATES PATENT OFFICE.

PETER JOHNSEN, OF MORGAN CITY, LOUISIANA.

FUEL-CHARGING AND CHARGE-FORMING APPARATUS FOR INTERNAL-COMBUSTION ENGINES.

1,122,124.

Specification of Letters Patent. Patented Dec. 22, 1914.

Application filed February 14, 1914. Serial No. 818,745.

To all whom it may concern:

Be it known that I, PETER JOHNSEN, a citizen of the United States, residing at Morgan City, in the parish of Saint Mary 5 and State of Louisiana, have invented certain new and useful Improvements in Fuel-Charging and Charge-Forming Apparatus for Internal-Combustion Engines; and I do hereby declare the following to be a full, 10 clear, and exact description of the invention, such as will enable others skilled in the art to which it appertains to make and use the same.

The present invention relates to multi- 15 cylinder explosive engines, and particularly to a fuel charging and explosive charge forming apparatus therefor whereby to use fuel of a lower and cheaper grade than is ordinarily employed, to the end of effecting 20 greater economy in the running of the engine and without any loss of efficiency.

The invention further contemplates a construction of apparatus of the type in question which may be equipped to any 25 ordinary well built engine without requiring any appreciable alteration in the engine structure; and one wherein the construction is not complicated, and not easily liable to get out of repair.

With these and other objects in view the invention consists in the novel details of construction and combination of parts more fully hereinafter disclosed and particularly 30 pointed out in the claim.

In the accompanying drawings forming a part of this application, and in which similar reference symbols indicate corresponding parts in the several views: Figure 1 is a top plan view, partly in section, of the 35 fuel charging apparatus. Fig. 2 is a central vertical sectional view thereof; and with parts in elevation, taken on the line 2—2 of Fig. 1. Fig. 3 is a central sectional view, with parts in elevation, of the charge forming 40 apparatus and showing its application to the engine; and Fig. 4 is a similar view of the charge forming apparatus on an enlarged scale.

The invention comprises a fuel charging 50 apparatus operable through the engine to force charges of liquid fuel from the source of supply to the respective cylinders of the engine, and which is automatically regulable through the speed of the engine to feed such 55 charges as are commensurate with the re-

quirement of the explosive mixture. The fuel thus delivered is formed into the proper charge by admixture with air through an apparatus mounted on the head of each cylinder, and such apparatus embodies 60 means for varying the time of delivery of the air and determining the moment when the explosive mixture is admitted into the cylinder.

The fuel charging apparatus consists of a 65 supporting plate or frame 1, adapted to be mounted on and between two cylinders of the engine, as for instance between cylinders two and three of a four-cylinder engine. A plurality of pump cylinders 2, are mounted 70 on the frame 1, and have their respective chambers each communicating with a pipe 3 leading to a source of fuel supply, and with a similar pipe 4 connecting the pump chamber with the mixing chamber of its respective charge forming device. The several feeding and delivery pipes 3 and 4 are provided with ball valves 5 and 6 to govern the inlet and outlet flow of the fuel, as will be 75 understood from the construction shown in 80 Fig. 2.

A pump plunger or piston 7 works in each of the pump cylinders and the several plungers are operated in rotation from the engine. The operative mechanism between 85 said plungers and the shaft 8 of the engine, consists of a plurality of arms 9 pivotally mounted on the frame at 10 and engaging, respectively, with the heads 11 of the plungers; and said arms are provided with 90 rollers 12 having engagement with a cam head 13 that is splined on a shaft 14, and said shaft is in turn connected to be driven from the crank shaft 8 through a miter gear 15. Each pump plunger is fitted with 95 a retraction spring 16 engaging with the cylinder and the plunger head 11. The cam head 13 is adapted to be adjusted on the shaft 14 through the engine governor 17 for effecting the variable throw of the several arms 9, and thereby automatically regulate 100 the amounts of liquid fuel admitted into and discharged from the several pump cylinders. And it will be noted that this automatic regulation of the liquid fuel feed 105 is directly controllable through the speed of the motor.

The charge forming apparatus comprises 110 a plug or head 18 mounted on a head 19 of each cylinder 20, and which is bored to pro-

vide a mixing chamber 21 having an outlet opening 22, which communicates directly with a chamber 23, of conical design, formed in the head 19. The mixing chamber 21 is adapted to receive the liquid fuel from the fuel charging device through its respective delivery pipe 4, and air under pressure is in like manner admitted into the mixing chamber 21 through the opening 24, communicating with the source of air supply by the pipe 25 and valve casing 26. A plunger or valve 27 operates within the mixing chamber 21 to control the outlet opening 22 at determinable periods and through the operation of the motor. Said valve 27 works through a stuffing box 28 in the head of the plug 18, and the valve stem 29 is engaged by a spring 30, through the nuts 31 for seating said valve. The torsion 20 of the spring 30 is regulable through adjusting the nuts 31, or by the cap 32 which has screw-threaded engagement with the end of the plug 18, as shown. A fulcrumed and two-armed lever (33-34) has one arm (33) engaging with the valve stem 29, and its other arm (34) is provided with a roller 35 to engage with the cam 36 on the shaft 37 that is adapted to be driven from the crank shaft 8. The air controlling valve 38 has its stem 39 engaged by the arm 40 of a two-armed lever, and the other arm, 41, of said lever is engaged by the roller 35 of the lever arm 34, whereby to actuate the air controlling valve through the lever arm 34 and simultaneously with the operation of the mixture releasing valve 21.

From the foregoing it will be clearly seen that the proper charge of compressed air is admitted into the mixing chamber 21 at the instant of release of the explosive mixture into the firing chamber, and as a consequence liquid fuel is delivered for explosion in a highly vaporized condition. And it will be further noted that the admixture of compressed air with the fuel is simultaneously timed to occur at the time set for release of the explosive charge into the cyl-

inder, *i. e.* through the angular adjustment of the cam 36 with respect to the lever arm 34.

The engine cylinder is provided with the usual air intake port 42 controlled by the valve 43; the exhaust outlet 44 is controlled by the valve 45, and is in turn operated through suitable mechanism connected with the crank shaft 8. A perforated grid or grate 46 is mounted in the cylinder adjacent the fuel inlet 23, and has for its purpose to further vaporize or atomize the admitted explosive charges due to its own heat as a result of the explosions in the cylinder.

It is obvious that those skilled in the art may vary the details of construction and arrangement of parts without departing from the spirit of my invention, and therefore I do not wish to be limited to such features except as may be required by the claim.

I claim:

The combination with a multi-cylinder explosive engine of a fuel charging and explosive charge forming apparatus therefor comprising mixing chambers for the respective engine cylinders; a plurality of pump-cylinders; means for admitting fuel into said pump-cylinders and therefrom into the respective mixing chambers of the engine cylinders; plungers operable in said pump-cylinders; means for actuating said plungers from the engine; means for admitting compressed air into said mixing chambers; controlling valves for said mixing chambers and air admissions, respectively; and common valve actuating means adapted to be operated from the engine to simultaneously open said controlling valves during the compression strokes of the respective pump plungers, substantially as described.

In testimony whereof, I affix my signature, in presence of two witnesses.

PETER JOHNSEN.
